Primary Examiner — Wan Laymon*Assistant Examiner* — Mark Booker(74) *Attorney, Agent, or Firm* — William S. Ramsey(57) **CLAIM**

The ornamental design for a recessed fire extinguisher cabinet, as shown and described.

DESCRIPTION

FIG. 1 is a perspective view of a recessed fire extinguisher cabinet showing my new design;

FIG. 2 is a front elevational view thereof;

FIG. 3 is a right side elevational view thereof; the left side elevational view is a mirror image of the right side; and, FIG. 4 is a top side plan view thereof, the bottom side plan view is a mirror image of the top side.

The back side of the recessed fire extinguisher cabinet is unornamented.

The broken line showing of the recessed fire extinguisher cabinet is included for the purpose of illustrating portions of the "article" and forms no part of the claimed design.
